UNITED STATES PATENT OFFICE.

MARCUS C. STEESE, OF DULUTH, MINNESOTA.

HYDROCARBON-BURNER.

1,296,709.

Specification of Letters Patent. Patented Mar. 11, 1919.

Application filed September 8, 1917. Serial No. 190,039.

To all whom it may concern:

Be it known that I, MARCUS C. STEESE, a citizen of the United States, and resident of Duluth, in the county of St. Louis and State 5 of Minnesota, have invented certain new and useful Improvements in Hydrocarbon-Burners, of which the following is a specification.

This invention relates to hydro-carbon burners.

10 One of the objects of the invention is to thoroughly atomize hydro-carbons in an improved manner to obtain efficient results.

Another object is to simplify and improve hydro-carbon burners to meet the various 15 requirements for successful commercial operation.

These and other objects are accomplished in general, by providing a hydro-carbon burner having steam or air and hydro-carbon conveying conduits arranged one within the other, the ends of said conduits terminating adjacent each other to form a narrow passage-way therebetween whereby high velocity steam or air has a double converging 25 speed increasing action on the hydro-carbon not only to draw the latter from its conduit but also to cause the hydro-carbon to be thoroughly atomized.

The invention is illustrated on the accompanying sheet of drawings, in which,

Figure 1 is a side elevation of my burner;

Fig. 2 is a fragmentary longitudinal sectional view of the same; and

Fig. 3 is a transverse sectional view taken 35 in the plane of line 3—3 of Fig. 2.

The various novel features of my invention will be apparent from the following description and drawings and will be particularly pointed out in the appended claims.

40 Due to the fact that hydro-carbons generally, and especially the higher grades of hydro-carbons, have greatly increased in cost, more or less effort is being made to burn the lower grades of hydro-carbons for heating purposes. However, some of the 45 lower grades of hydro-carbons are extremely sluggish, thereby making it difficult to get the heavier hydro-carbons in such condition as to burn the same efficiently. Tar, for example, is one of the relatively heavy hydro-carbons which may be burned efficiently for heating purposes if the same is in proper condition. The main problem, therefore, of utilizing the relatively heavy hydro-carbons 50 such as tar and the like, is to thoroughly

disintegrate or atomize such heavy hydrocarbons so that they may be burned efficiently. To accomplish this end I have provided a hydro-carbon burner 10 having an outer fluid-conveying conduit 11 through which any suitable atomizing medium may pass, and a hydro-carbon-conveying conduit 12 within the fluid-conveying conduit 11. In this particular instance let it be assumed that the heavy hydro-carbon which is being 55 treated is tar 13 shown within the conduit 12. It will be noted that the active end of the conduit 11 is in the form of a stream line curve and extends inwardly toward the active end of the tar-conveying conduit 12. The conduits converge toward each other at their ends and form a relatively small passageway 14 between the conduits 11 and 12. The active end of the tar-conveying conduit is beveled exteriorly, thereby co-operating 60 with the inwardly extending end portion of the fluid-conveying conduit 11 to determine the path of movement of atomizing medium which passes outwardly from the conduit 11 through the narrow passageway 14. The arrangement and shape of the walls of the two conduits, at their active ends is such as to cause the velocity of the atomizing medium at the small annular passageway 14 to be greatly increased. The atomizing medium is preferably high pressure steam or air. When I refer to a conduit or tube having a stream line curve or more particularly to a stream line curve, I mean a curve so designed that the flow of fluid along that curve 65 is produced with the least amount of resistance and the least loss of energy; also it is a curve which in the flow of fluids transfers pressure and flow to velocity and flow. When I refer to a stream line flow, I mean a 70 flow of fluid the cross section of which at consecutive points is proportionate inversely to the velocity at the respective points i. e., the stream line flow transfers pressure into velocity with the least possible loss of energy. It may or may not be within a tube or chamber. To clarify the exact action of the atomizing medium on the tar, let it be assumed first that the opening or passageway 14 extends through but a few degrees 75 at the top and end of the tar conduit 12. Under such conditions the atomizing medium would flare outwardly and downwardly, taking a downward path across the front of the steam conduit 11. Now assume 80

that in addition the passageway 14 extends but a few degrees at the bottom and end of the tar conduit 12. Under such conditions there would be a second high velocity stream 5 of the atomizing medium, but in this case extending or flaring upwardly and outwardly across the front end of the steam conduit 11. These two high velocity streams cross the paths of each other in a very 10 apparent manner. Now assume, which is the actual case, that the passageway 14 extends through 360 degrees. Under such conditions there are an infinite number of such 15 high pressure streams of the atomizing medium acting upon each other in a manner to form a second stream line flow, shown by the lines "c," the narrowest part being at the point 16. The stream line flow is confined within and bounded by stream line curves formed 20 in the air and they are as positively defined as if the flow were within a tube shaped with stream line curves. It naturally follows that the velocity of the atomizing medium is the greatest at this point 16, and is 25 considerably greater at this point than at the passageway 14. The practical effects and results, among others, are these; that a partial vacuum is formed slightly in advance of the end of the tar conduit 12 and between 30 the end of the tar conduit and the narrowest part 16 of the second stream line flow, thereby causing the tar 13 to be drawn from its conduit; that the high pressure atomizing medium of the first stream line flow acts to slice off minute globules of tar; 35 that the atomizing medium of the secondary stream line flow completely disintegrates and atomizes the tar so that the same may be burned efficiently. The vacuum is caused 40 primarily by the second stream line flow and secondarily by the first stream line flow. By means of this arrangement a minimum amount of steam or air, as the case may be, is used and at a maximum velocity to accomplish 45 the desired results. The high speed steam or air acts on the tar to draw the same to a point such as shown at 15.

The hydro-carbon may be supplied from any suitable source to the rear end of the 50 hydro-carbon-conveying conduit 12 and the atomizing medium may be supplied from any suitable source through a pipe 17 which connects with the conduit 11.

It is highly essential that the hydro-carbon-conveying conduit should be located 55 centrally with respect to the steam or air conveying conduit 11. For this purpose I have provided a plurality of longitudinally spaced sets of set screws 18 which are 60 threaded through the steam or air conveying conduit 11 and engage the external surface of the hydro-carbon-conveying conduit 12. By proper manipulation of the set screws the hydro-carbon-conveying conduit 65 12 may be accurately located centrally with

respect to the steam or air conveying conduit 11. It will be appreciated that other centering means may be provided for the hydro-carbon-conveying conduit 12. The rear end of the hydro-carbon-conveying 70 conduit 12 is threaded through a collar 19 which in turn is threaded into a T-member 20 which also receives the steam or air conveying pipe 17. By means of this arrangement the hydro-carbon-conveying conduit 75 12 may be accurately adjusted longitudinally with respect to the other conduit 11 to position the active ends thereof in a manner to produce the best results. When the conduit 12 is thus positioned the same may be 80 locked by a lock nut 21.

As mentioned above, the hydro-carbon conveying conduit lies wholly within the fluid conveying conduit, or the active ends of said conduits lie substantially in the 85 same transverse plane, the active end of said conduits being associated with respect to each other in such a manner that a relatively narrow opening is formed for the passage of high pressure fluid. The opening of the hydro-carbon conveying conduit is relatively large with respect to the opening for the high pressure fluid, said conduit terminating in a knife edge, the high pressure fluid in passing through the narrow 95 opening between said conduits acting upon the hydro-carbon in such a manner as to draw the same from its conduit by suction, and slicing the hydro-carbon off to thoroughly disintegrate the same for complete 100 combustion.

It is apparent that there may be various modifications of the invention as herein particularly shown and described, and it is my intention to cover all such modifications 105 which do not involve a departure from the spirit and scope of the invention as set forth in the following claims.

I claim:

1. In a hydro-carbon burner, the combination of fluid and hydro-carbon conveying conduits, the latter being wholly within the former, said conduits forming a relatively narrow opening for the passage of high pressure fluid, the opening of the hydro-carbon conveying conduit being unobstructed and such as to permit the high pressure fluid to draw the hydro-carbon from its conduit by suction, the openings of the conduits being arranged in a manner such that the hydro-carbon is sliced off by the high pressure fluid.

2. In a hydro-carbon burner, the combination of fluid and hydro-carbon conveying conduits, the active ends of which terminate substantially in the same transverse plane, said conduits forming a relatively narrow opening for the passage of high pressure fluid, the opening of the hydro-carbon conveying conduit being unobstructed.

ed and such as to permit the high pressure fluid to draw the hydro-carbon from its conduit by suction, the openings of said conduits being arranged in a manner such that 5 the hydro-carbon is sliced off by the high pressure fluid.

3. In a hydro-carbon burner, the combination of fluid and hydro-carbon conveying conduits, the active ends of which terminate 10 adjacent each other to form a relatively narrow opening for the passage of high pressure fluid, the hydro-carbon conveying conduit having an unobstructed opening and terminating in a knife edge past which the 15 high pressure fluid passes for drawing the hydro-carbon from its conduit by suction, the opening through which the high pressure fluid passes being arranged in a manner such that the hydro-carbon which is

drawn from its conduit is sliced off for thoroughly disintegrating the hydro-carbon. 20

4. In a hydro-carbon burner, the combination of fluid and hydro-carbon conveying conduits, the hydro-carbon conveying conduits being arranged to form a relatively 25 narrow opening for the passage of high pressure fluid, the opening of the hydro-carbon conveying conduit being unobstructed and relatively large with respect to the opening for the high pressure fluid, the 30 openings of said conduits being arranged in a manner such that the hydro-carbon is drawn from its conduit by suction and sliced off by the high pressure fluid.

Signed at Duluth, Minnesota, this eight- 35
eenth day of August, 1917.

MARCUS C. STEESE.
